his Attorney.

UNITED STATES PATENT OFFICE.

JAMES E. LOSE, OF WILKINSBURG, PENNSYLVANIA.

TUYÈRE COOLER.

Application filed January 21, 1925. Serial No. 3,873.

This invention relates to blast furnace coolers and more particularly to means for and method of forming a sealed joint between the cooler and furnace wall.

5 The principal object is to provide a cooler for blast furnaces which will automatically seal with the furnace wall when the cooler is driven home in the cooler opening.

Another object is to provide a cooler for 10 blast furnaces having the novel construction, combination, and design of parts hereinafter described, and illustrated in the accompanying drawings.

In the drawings—

15 Figure 1 is a sectional elevation of the lower end of a blast furnace showing a cinder notch and tuyère cooler having my invention applied thereto.

Figure 2 is an enlarged elevation of a 20 cooler having my invention applied thereto.

Figure 3 is an enlarged elevation of a cooler mounted in a section of furnace wall.

25 Referring more particularly to the drawings, the letter A designates the portion of furnace wall shown as a whole, which comprises the bosh portion 2, the hearth portion 3, and the stack portion 4 which is broken away.

The bosh portion 2 is provided with a 30 tapered cinder notch opening 5 in which is mounted a tapered cinder notch cooler 6.

The bosh portion 2 also is provided with the usual tapered tuyère openings 7, only one of which is shown in the drawings, and 35 a tapered tuyère cooler 8 and tuyère 9 are mounted in said openings.

The hearth is provided with a plurality of the usual cooling plates 10.

The cinder notch opening 5 and tuyère 40 opening 7 are each tapered inwardly and the coolers which are mounted in the openings are likewise tapered to facilitate withdrawing of the burned-out coolers.

The cinder notch and tuyère coolers 6 and 45 8, respectively, are formed with hollow walls through which water is circulated for cooling. These coolers frequently burn out and must be removed and replaced while the furnace is in operation.

50 It is well known in the art, that the removing of a burned-out cooler and replacing it with a new cooler is a dangerous and dif-

ficult operation, due to the escape of heat, gases, flame, etc. during the operation.

Heretofore it has been the practice to pull 55 out the burned-out cooler, insert a new cooler and force the cooler into position, then to force suitable packing by the use of paddles, bars and other tools, around the cooler to form a sealed joint between the cooler 60 and furnace wall. This operation exposed the workmen to the escaping gases, flames, etc. for a considerable time.

The present invention provides an improved form of cooler having a packing ring 65 12 of asbestos loosely mounted thereon, which ring is mounted on the cooler at a point materially beyond its rear end, and due to the taper of the cooler, at a point where it will readily fit within the cooler 70 opening. The cooler and ring are thus forced into the cooler opening together, and the cooler is then driven home, forcing the ring 12 back a short distance on the cooler and compressing it between the sides of the 75 cooler opening and the cooler, thereby automatically forming a sealed joint between the cooler and furnace wall and preventing the escape of the gases and flames, which have heretofore been so bothersome and dangerous 80 to the workmen.

The packing ring 12 forms a complete seal. It will be understood, however, that if desired other packing material may be forced in around the cooler back of the ring, al- 85 though such packing is not necessary.

The cinder notch and tuyère coolers 6 and 8 are of substantially the same construction. Therefore, only the cinder notch cooler 6 has been shown in enlarged detail.

I claim—

1. The combination with a blast furnace wall having at least one inwardly tapering cooler opening therein, of a tapered cooler adapted to be inserted in said opening, and an asbestos packing ring mounted on said cooler and adapted to be automatically moved longitudinally of said cooler as said cooler is driven home in said opening, thereby compressing said ring and forming a 100 sealed joint between said cooler and furnace wall.

2. The combination with a blast furnace wall having at least one inwardly tapering

cooler opening therein, of a tapered cooler adapted to be inserted in said opening, and a compressible packing ring of non-combustible material loosely mounted on said 5 cooler at a point materially forward of the point where it is desired to have it form its seal, said cooler being adapted to be driven home in said cooler opening, and said ring being free to and adapted to move rearwardly along said cooler as said cooler is 10 driven home to thus form a sealing connection between the furnace wall and cooler.

In testimony whereof I have hereunto set my hand.

JAMES E. LOSE.
